PACKAGING FOR CANDY CANES

Christos M. Sogas and Sam M. Sogas,
Kansas City, Mo.

Application February 24, 1948, Serial No. 10,354

2 Claims. (Cl. 99—180)

1

The present invention relates in general to packaging candy canes, the objective being to produce a package whereby long distance shipment of goods of this character on a commercial basis is feasible.

The manufacture and sale of candy canes is a seasonal business by reason of the fact that the demand for the canes is very heavy at and around Christmas but comparatively light during the balance of the year. In the past production of the canes in preparation for this seasonal demand virtually always has been a local business carried on within the immediate retail area for the goods. Attempts have been made to serve remote areas from a central location but these have been abandoned because of the high rate of breakage occurring in the course of shipment.

A broken candy cane has no sales value at the average retail candy counter; its traditional function is to gladden the Christmas scene as well as please the palate and once broken it no longer is a satisfactory decoration for the Christmas tree or an appropriate gift for a child. In short it is substantially a total loss. Unfortunately the canes are so fragile by nature that it is difficult even under comparatively favorable conditions to bring them unbroken to the retail store counters for ultimate sale. Under the less favorable conditions encountered in shipping them over material distances breakage of 50% of the starting lot has not been unusual. In the light of these facts it is, of course, easy to see why long distance shipment has been considered commercially impractical and why over a long period of years the manufacture of the canes has remained essentially a local business.

The object of the present invention is to provide packaging for candy canes which will make possible long distance shipment with little or no breakage.

Another object is to provide packaging of this character at a sufficiently low cost to be practical from a commercial standpoint, it being obvious that if the packaging is expensive it will defeat its own purpose of making possible the widespread low-cost distribution of candy canes from a central location.

Another object is to provide packaging which is attractive and adapted to maintain the goods clean and sanitary.

Other and further objects of the invention together with the features of novelty will appear in the course of the following description.

In the accompanying drawings which form a part of the specification and are to be read in

conjunction therewith and in which like reference numerals are employed to indicate like parts of the various views,

Fig. 1 is a perspective view of a box of candy canes wrapped and packaged according to the invention, part of the box having been cut away for purposes of illustration,

Fig. 2 is an end view of one package or bundle of candy canes,

Fig. 3 is a plan view showing the manner in which canes are arranged on a strip of corrugated paper preparatory to wrapping,

Fig. 4 is a plan view showing an alternate arrangement of the canes preparatory to wrapping, and

Fig. 5 is an end view of the finished package produced by the arrangement illustrated in Fig. 4.

The candy canes to be packaged first are wrapped individually for purposes of sanitation, transparent paper preferably being employed so that the goods ultimately may be displayed in shops and inspected by customers without being touched and without danger of contamination by dust or otherwise. In the drawings the canes are identified by the reference numeral 10 and it will be noted that the individual transparent wrapping 12 is a tapered envelope or sleeve twisted at the head and foot of the cane as shown at 14 to close the ends of the wrapping and maintain same in place.

The canes are gathered in bundles with the aid of a strip of corrugated paper 16. For one ounce canes it has been found best to use 35 pound to 50 pound corrugated paper, it being understood of course that the optimum grade of paper will vary with the weight and size of the canes. It is important that the width of the strip 16 be slightly greater than the length of the canes so that when they are arranged crosswise of the strip, as shown in Figs. 3 and 4, the paper will extend slightly beyond the extremities of the canes.

An even number of canes (preferably 6) are placed in each bundle, half of them having their heads at one end of the bundle and the remaining half having their heads at the opposite end.

To achieve this result the strips 16 are placed flat on a table and the canes are arranged on the strips, either in the fashion indicated by Fig. 3 or as illustrated by Fig. 4.

In Fig. 3 it will be noted that the 6 canes are alternated in direction, i. e., the cane on the left has its head near one edge of the strip, the next cane's head is adjacent the opposite edge, the third is placed like the first, the fourth like the

second and so on. The left-hand cane is spaced inwardly from the left-hand end of the strip by a distance approximately equal to the width of the cane at its head and the initial step in the wrapping procedure is to fold this end of the strip over the first cane. This forms a long pocket containing the first cane. The pocket with the cane therein is rolled forward (i. e., to the right as shown in Fig. 3) until it covers the second cane, this process being repeated for the next cane and continuing until the roll finally passes over the last cane. As the rolling progresses the spacing of the canes along the strip is adjusted so that the heads of the canes are in substantial parallelism in the bundle as indicated by Fig. 2. The right-hand end of the corrugated paper is wrapped on around the bundle and fastened in place by an adhesive strip 18.

Referring to Fig. 4 the wrapping is effected in the same fashion as just described, the only difference being in the initial arrangement of the canes on the strip and the final position they consequently assume in the bundle.

The Fig. 3 arrangement results in a bundle of the kind shown in Fig. 2 wherein the three canes on the left have their heads toward the observer and the three on the right have their heads away from the observer; the Fig. 4 arrangement on the other hand results in a bundle of the kind shown in Fig. 5 wherein the first cane on the left has its head toward the observer, the next one has its head away from the observer, the third has its head in the same direction as the first, the fourth in the same direction as the second, and so on. In other words, the canes in the bundle of Fig. 5 are alternated in direction.

According to either starting arrangement a balanced bundle is achieved, half of the canes having their heads at one end of the bundle and the other half being pointed in the opposite direction. Six-cane bundles are preferred because the rolls are nearly circular in transverse cross section; as indicated hereinbefore, however, the number of canes to the roll may be varied.

For shipment the bundles are boxed in corrugated cartons 20 as shown in Fig. 1. It is important that the width of the carton conform with the width of the strips 16 so that there can be no endwise movement of the rolls. This leaves some clearance between the ends of each cane and the inside of the carton, the twisted tuft 14 of the individual wrapping about the cane serving as a spacing cushion to maintain both ends of the cane spaced inwardly from the carton walls. The length and depth of the carton should be such as to prevent any substantial movement of the rolls transverse to their axis, yet, of course, should not be so tight as to materially compress any of the rolls.

Canes packaged as described have been shipped in quantity lots over long distances through ordinary shipping channels and despite the inherently fragile character of the canes and the rough treatment they received the breakage experienced was nil.

From the foregoing it will be seen that this invention is one well adapted to attain all of the ends and objects hereinbefore set forth together with other advantages which are obvious and which are inherent to the structure.

It will be understood that certain features and subcombinations are of utility and may be employed without reference to other features and subcombinations. This is contemplated by and is within the scope of the claims.

Inasmuch as various embodiments of the invention may be made without departing from the scope thereof, it is to be understood that all matter herein set forth or shown in the accompanying drawings is to be interpreted as illustrative and not in a limiting sense.

Having thus described our invention, we claim:

1. A candy cane package comprising a number of candy canes disposed side by side with their heads in substantial parallelism, the heads of substantially half of the canes being at one end of the package and the heads of the rest of the canes being at the opposite end, a strip of corrugated paper having one end between the two center canes, said strip wound in a continuous spiral with successive layers passing between adjacent ones of the canes and the outermost layer embracing the outermost canes, the width of the strip being greater than the length of the cane, flat walls abutting the end of the roll formed by said spiral strip, and cushioning means between at least one end of each cane and the adjacent one of said walls.

2. A candy cane package comprising a number of candy canes disposed side by side with their heads in substantial parallelism, the heads of substantially half of the canes being at one end of the package and the heads of the rest of the canes being at the opposite end, a strip of corrugated paper having one end between the two center canes, said strip wound in a continuous spiral with successive layers passing between adjacent ones of the canes and the outermost layer embracing the outermost canes, the width of the strip being greater than the length of the canes, flat walls abutting the end of the roll formed by said spiral strip, and an individual wrapping on each cane formed to provide a cushion between the end of that cane and the adjacent one of said walls.
